CLAIM

The ornamental design for a pedicure basin base, as shown and described.

DESCRIPTION

FIG. 1 is an upper perspective view of the pedicure basin base according to my design, showing portions of the pedicure basin base in broken lines.

FIG. 2 is a front elevation view thereof, showing portions of the pedicure basin base in broken lines;

FIG. 3 is a back elevation view thereof, showing portions of the pedicure basin base in broken lines;

FIG. 4 is a top plan view thereof, showing portions of the pedicure basin base in broken lines;

FIG. 5 is a bottom plan view thereof, showing portions of the pedicure basin base in broken lines;

FIG. 6 is a side elevation view thereof; an opposite side elevation view being a mirror image thereof, showing portions of the pedicure basin base in broken lines; and,

FIG. 7 is another upper perspective view thereof, showing accessories of the pedicure basin base in broken lines.
The broken lines indicate unclaimed portions of the design and environment.

1 Claim, 3 Drawing Sheets
